UNITED STATES PATENT OFFICE

91,942

DESIGN FOR A STORE FRONT

Russell R. B. Jerry, Minneapolis, Minn.

Application November 1, 1933, Serial No. 49,629

Term of patent 14 years

To all whom it may concern:

Be it known that I, RUSSELL R. B. JERRY, a citizen of the United States, residing at Minneapolis, in the county of Hennepin and State of Minnesota, have invented a new, original, and ornamental Design for a Store Front, of which the following is a specification, reference being had to the accompanying drawings, forming part thereof.

Figure 1 is a front elevation of the store front showing my new design; and Figure 2 is a side elevation of the store front showing my new design.

I claim:

The ornamental design for a store front, as shown.

RUSSELL R. B. JERRY.
